Primary Examiner — George D Kirschbaum*Assistant Examiner* — Clese Moore, Jr.(74) *Attorney, Agent, or Firm* — Harness, Dickey & Pierce, P.L.C.(57) **CLAIM**

The ornamental design for an automobile control component, as shown and described.

DESCRIPTION

FIG. 1 is a perspective view of an automobile control component as a play module;

FIG. 2 is a front plan view thereof;

FIG. 3 is a top plan view thereof;

FIG. 4 is a left side elevational view thereof;

FIG. 5 is a right side elevational view thereof; and,

FIG. 6 is a bottom plan view thereof.
